GEORGE L. MATHENEY, OF BRIDGEPORT, OHIO, ASSIGNOR OF ONE-HALF TO
J. O. HOWELLS, OF BRIDGEPORT, OHIO.

TROLLEY-GUARD.

No. 857,643.

Specification of Letters Patent.

Patented June 25, 1907.

Application filed July 12, 1906. Serial No. 325,863.

To all whom it may concern:

Be it known that I, GEORGE L. MATHENEY, a citizen of the United States of America, and a resident of Bridgeport, county of Belmont, and State of Ohio, have invented certain new and useful Improvements in Trolley-Guards, of which the following is a specification.

My invention relates to new and useful improvements in trolleys, and more particularly to a trolley guard; and it consists in the particular construction, arrangement and combination of parts which will hereinafter be fully described.

The object of the invention is to provide a simple, cheap, durable and efficient guard for preventing trolleys from jumping off the trolley wire.

A further object is to provide a trolley guard which serves the same purpose when the car to which it is applied is reversed as when traveling forward, and which may be applied to any ordinary trolley without requiring a change to be made in the harp or wheel. And a still further object is to provide a guard which will readily pass through switches and under cross-wires without interference.

In describing the invention in detail, reference is herein had to the accompanying drawings, forming a part of this specification, in which—

Figure 1 is a side elevation of the invention; Fig. 2 is a rear elevation of the same; and Fig. 3 is a cross section of the same.

Referring to said drawings, in which like reference-numerals designate like parts throughout the several views—1 indicates the trolley harp and 2 the trolley wheel, both being of an ordinary type of construction. Mounted in a substantially vertical position upon the wheel spindle 3 at opposite ends thereof close against the members 4 of the harp is a longitudinal arm 5. A diagonally-extending cross-channel 6 is provided in the inner face of the arm 5 near its upper end, forming shoulders 7 which fit close against the opposite edges of the members 4 of the harp, means being thus provided whereby the arms are rigidly held in substantially vertical positions. Carried by the lower end of each arm 5 is an angular lug 8 having a vertical hole therethrough in which is slidably held the stem 9 of a spring-controlled

element 10 which lies close against said arm 5. Said element 10 consists of a longitudinal body portion 11 having an integral head 12 with a rounded edge 13. Provided in said body portion and head is a longitudinal slot 14 in which is held a rectangular block or slide 15 which is carried by the spindles 3, said block or slide being adapted for guiding said head vertically in its movements, as will hereinafter be explained. The spindle 3 projects outward beyond the slotted elements 10 and has threaded upon its ends securing-nuts 16, as shown.

A coil-spring 17 encircles each stem 9, the lower end of said spring resting upon said lug 8 and the upper end of said spring resting against the lower end of the body portion 11 of the element 10, whereby said element is normally held in an elevated position, as shown in full lines in Fig. 1.

The heads 12 project vertically above the wheel 2 at opposite sides thereof, and are each provided with an inwardly-directed beveled lip 18 at a point above the edge of the wheel, said lips being adapted to be engaged by the trolley wire when it slides from the wheel and to thus guard against the trolley leaving the wire.

As is apparent, when the heads 12 come into contact with a cross-wire, a supporting-wire, or a trolley wire at a switch, said heads are thereby forced downward against the tension of the springs 17, permitting the trolley to unobstructedly pass thereunder.

Owing to the fact that the tension of the spring 17 is but little more than sufficient to normally hold the head 12 elevated above the trolley wheel, a slight pressure upon the rounded edge 13 at any point is sufficient to force said head downward to a level with the trolley wheel.

The movement of the element 10 being vertical, and the edges 13 being rounded, the device works the same whether the trolley be traveling forward or rearward.

The opposite elements 10 being in no wise connected, said elements operate independently of each other—a feature which is particularly desirable in a device of this character for obvious reasons.

It will be noted that various minor changes may be made in the construction and arrangement of some of the parts composing the invention without departing from the

spirit or scope thereof. I do not, therefore, desire to limit myself to the precise construction and arrangement of parts herein shown and described.

5 Having thus described my invention, what I claim as new, and desire to secure by Letters Patent, is—

In a device of the character described, the combination with a trolley wheel, a wheel 10 axle, and a trolley harp, of a longitudinal stationary arm mounted in a substantially vertical position on said axle against the harp at each side thereof, an angular lug having a vertical hole therethrough carried by 15 the lower end of said arm, and a vertically-movable element mounted on each end of said axle against said arm, said element comprising a body portion having a longitudinal slot therein through which the axle extends,

a guide-block carried by the spindle and 20 slideable in said slot, a stem carried by the lower end of the body portion, the lower end of said stem being movably held in the hole in the lug, a coil spring carried by said stem between said body portion and said lug, a 25 head carried by said body portion, said head being normally held with its upper edge elevated above the trolley wheel, said upper edge being rounded, and a beveled inwardly-directed lip carried by said head above the 30 edge of said wheel, substantially as and for the purposes set forth and described.

In testimony whereof I affix my signature in presence of two subscribing witnesses.

GEORGE L. MATHENEY.
